UNITED STATES PATENT OFFICE.

LEONARD ADAMS, OF BUFFALO, NEW YORK.

ANNULAR STEAM ROTARY MOTOR.

1,345,526.

Specification of Letters Patent.

Patented July 6, 1920.

Application filed October 28, 1918. Serial No. 260,031.

To all whom it may concern:

Be it known that I, LEONARD ADAMS, a citizen of the United States of America, residing at 468 Monroe St., in the city of Buffalo, county of Erie, and the State of New York, have invented a new and useful Annular Steam Rotary Motor, of which the following is a specification and description.

My invention relates to improvements in annular steam rotary motors in which rotors are revolved by steam pressure which is controlled by rocker or oscillatory valves. These drawings, specifications and descriptions as set forth, illustrate and describe my invention in compound design for use in automobiles. Two complete motors are put together, each to operate a rear wheel of the vehicle.

The objects of my improvements are; first, to provide an annular steam rotary motor having steam-tight, non-back-resistant or compressionless rotors; second, to provide an annular steam rotary motor having reliable valves and a steam cut-off device or timer that will save steam and accelerate the speed; and third, to provide a light, compact and powerful annular steam rotary motor for self-moving vehicles, motor-boats, airplanes etc., and also for manufacturing and commercial work.

I attain the above objects by the mechanisms illustrated in the accompanying drawings and specification, in which—

Figure 1 is a front elevation of the motor with part of the casing removed.

Fig. 2 is a horizontal section of the entire lower half of the motor.

Fig. 3 is a side elevation with casing removed.

Fig. 4 is a vertical section on the line *a—a* of Fig. 1.

Fig. 5 is a side elevation having portions broken away.

Fig. 6 is a rear elevation of the steam cut-off device or timer.

Fig. 7 is a vertical section of the steam cut-off device or timer.

Fig. 8 is an enlarged sectional view of a combination rocker-oscillatory valve.

Fig. 9 is an enlarged sectional view of a valve and steam *T*.

Fig. 10 is a sectional view of a rotor and the combination valve lift and steam obstructions.

Fig. 11 is a vertical section of the rotors on the line *b—b* of Fig. 10.

Fig. 12 is a side view of the reversing mechanism.

Fig. 13 is a top view of the reversing mechanism.

Similar reference numerals indicate corresponding parts throughout the several views of the drawings.

The cylindrical flanged housing 1 having the rotor division wall 2, the rotor housing plates 3 and 4 securely and perfectly bolted to housing 1, and the supporting casing 5 carrying a removable casing 6, is securely fastened to the axle housing 7, making with the plates 3 and 4, the frame of the motor. The housing 1 and the housing plates 3 and 4 as shown, are drilled for bolting and machined perfectly for a steam-tight fitting.

The hollow or tubular shafts 10, having solid rings 11 to which are securely and snugly bolted the rotors 29, the eccentrics 13, and the steam cut-off device or timer shown in Figs. 6 and 7, have a simple slot 12 in one end and into which a dog 14 is fitted. These dogs 14 are securely fastened to the driving axles or shafts of an automobile or vehicle and thus connect the motor directly to the rear wheels of the vehicle. The plates 3 and 4 carry the roller bearings 8, the pumps 9, and the valve bearings 25 of the motor.

The steam enters the motor through the main supply pipe 16, into the distributing chamber 17 which is fastened to the motor housing 1 by flange 18, and in which the steam receives the proper supply of lubricating oil held in reservoir 20, and delivered into said chamber 17 through pumps 19. Fig. 4. The steam is then branched off into the specially designed valve *T*'s 21, Fig. 9, through the tubes 22. From these valve *T*'s 21, the steam passes into perfectly machined lead tubes 23 which are suitably fastened to said *T*'s 21 at the one end and are closed at the other end, and contain slots as shown in Fig. 9, to allow or lead the steam into the valve slots. The slots in said lead tubes 23, together with corresponding slots in the cut-off or oscillatory valves 24, the slots in the stationary valve 105 bearings 25, and the steam outlets 26 in the rocker valves 27, are so placed to correctly control and lead the steam into the steam channels 28 where it acts against the combination valve lift and steam obstructions 30 on the rotors 29 Figs. 10, 9, 8 and 5. These combination valve lift and steam obstruc-

tions 30 have elongated elevated surfaces and sloping ends with openings 63 of suitable proportion and shape therein which lead to steam obstruction chambers 64 located beneath the sloping ends and in which are positioned packing members 55 which, in connection with the walls of the said steam obstruction chambers 64, form a barrier or obstruction upon which the steam pressure 10 and expansion acts to rotate the rotors 29 upon which they are suitably fastened. As the rotors 29 revolve, the steam contained in the steam channels 28 behind the rocker valves 27, is released and pushed out 15 through the exhaust slots 31 in the rocker valves 27 into exhaust chamber 32, and thence through the exhaust ports 33 into the entire motor casing, thereby lubricating all the working parts of the motor by the 20 oil contained in the steam. From the motor casing the steam is led through the exhaust pipe 34, into a condenser.

The combination rocker and oscillatory valves are both automatic and mechanical 25 acting and consist of a lead tube 23 carefully fitted into an oscillatory valve 24 which is snugly fitted into a stationary valve bearing 25 upon which a rocker valve 27 is fitted and moves. All have, as shown 30 in Figs. 5, 6, 7, 8 and 9, corresponding slots for controlling the passage of steam.

The automatic working of the combination rocker and oscillatory valves is through the combination valve lift and steam obstructions 30 on the rotors 29, which causes to rock when revolving, the rocker valves 27 which are held in a forward or reverse position by a reversing device controlling the springs 35 attached to the rocker valves 40 27. The rocking causes the steam outlets 26 in the rockers 27, to move away from the slot openings in the stationary valve bearings 25, thereby causing the valve to open and close automatically. The rocker valve 45 27 has a concave surface or cavity at each end, and outlets 26 are positioned, so that the resultant steam pressure in chamber 28 against the concave surface automatically balances the rocker 27, thereby allowing the 50 free movement and giving the correct position to the valve under any load, without pressure friction on the rotors.

The mechanical working of the combination rocker and oscillatory valves is through 55 the steam cut-off device or timer Figs. 6 and 7, operating the oscillatory valve contained in this combination valve. This steam cut-off device or timer as shown, consists of a large double camlike shaped disk 60 37 having a set of gears and a collar onto which is carefully fitted a similar but movable or advancing camlike shaped disk 38 to which is attached a crescent shaped ratchet 61; a collar plate 39 for holding said disk 65 38 in position, is suitably bolted to the col-

lar of disk 37 which in turn, is fastened to the hollow shaft 10 of the motor by a key 36; a cylindrical ratchet 40 placed inside the hollow shaft 10, is held in position or moved by a controlling gear 41 attached to a controlling rod 42 operated by either a hand or foot lever; and cut-off device or timer levers 43, which are held in position by springs 62 and operated by the camlike outlines of 37 and 38, are fitted with bearings, are suitably mounted and are connected to the cut-off or oscillatory valves 24 by the connecting levers 44.

The operation or working of this cut-off device or timer as illustrated and described, is as follows: The controlling rod 42 to which is attached gear 41, moves the cylindrical ratchet 40 forward to any desired position, thereby setting in motion the set of gears attached to disk 37 with 75 which it is in mesh. This set of gears on disk 37, which also is in mesh with a crescent shaped ratchet 61 attached to the movable disk 38, causes when set in motion, said movable disk 38 to move or advance. 80 When this disk 38 is moved forward or advanced, it prematurely lifts the disk levers 43 causing the cut-off or oscillatory valve 24 to move so that its slots are not in alignment with the slots in the stationary 85 valve bearing 25, thus closing the slots and cutting off the steam supply at any desired point in a working stroke of the rotors 29. It is obvious that when the advancing disk 38 is again returned to its neutral position, 90 the valves are again in operation during the entire working strokes of the rotors.

The combination rocker and oscillatory valves are perfectly fitted and suitably bolted on the housing plates 3 and 4 and are 105 made steam tight by means of packing boxes 45 on the stationary valve bearings 25 and on the valve T's 21.

The reversing device is operated by rod 46 passing through the hollow rod 42 which 110 is slotted at 47, to allow the fastening of the disks 48 to said rod 46. The disks 48, moved through the forward or backward movement of the rod 46, required to reverse the motor, operate a circular lever 49 which has its 115 bearings on the cut-off valve tubes 24 at the valve T's 21 and to which is fastened a gear ratchet 50. This gear ratchet 50 causes gear 51 to move up or down, thereby raising or lowering the valve spring lifts 52 which 120 are fastened onto a shaft 53 carrying said gear 51. The movement of the valve spring lifts 52 up or down on either valve spring 35 of the rocker valves 27, causes either the upper or lower outlets 26 in the rocker 125 valves 27 to work and produces either a forward or reverse rotation of the rotors 29.

The rotors 29 are perfectly machined to fit snugly and perfectly in the motor 130 housings and make a steam-tight fitting by

the steam pressure causing the flanges 54, which form the channels 28 on the rotors 29, to sufficiently expand without pinching. Each rotor 29 is fitted with two combination valve lift and steam obstructions 30 which are securely fastened in the channels 28 in positions diametrically opposite each other, and which are designed as shown, with ends sloping in such a manner so as to 10 easily and correctly operate the rocker valves 27 in the steam channels 28 without strain or unnecessary wear on the rotors 29, and having openings 63 of suitable proportion and shape in said sloping surfaces of these ends so as to allow the steam pressure to reach the camlike contrivances or packing members located in the steam obstruction chambers and which make the valve lifts or obstructions 30, steam tight in the 20 rotor housings. These camlike contrivances as shown in Fig. 10, consist of cam shaped bearings 55 which are securely and perfectly fitted in place of bolts 56 and held in suitable seats by springs 57, and make, when 25 under pressure, the rotors 29 steam tight in the rotor housings by being carefully seated. The seating is to be so, that the action of the steam pressure will not cause the cam shaped bearings 55 to bear too 30 heavily upon the inner surfaces of the housings thereby avoiding unnecessary friction and pinching.

The motor, which is designed in multiple form, has two rotors 29 fastened, as shown 35 in Fig. 2, onto a ring 11 which is carried on a hollow-shaft 10. They are positioned in such a manner so that each rotor 29, having combination valve lift and steam obstructions 30 as described above, will be diametrically perpendicular to each other, thereby producing a smooth and continuous rotation in either direction.

The rear housing plate 58 and the front housing plate 59 which carries the exhaust 45 outlet, together with the removable plates 60 which give access to the valve packing boxes 45, are all fastened steam-tight to the frame of the motor.

I am aware that prior to my invention annular steam rotary motors have been made, 50 therefore I do not claim such a motor broadly, but

I claim, and desire to secure by Letters Patent:

55 1. In combination with an annular steam rotary motor having a suitable casing, two annular steam rotary motor rotors, each having a pair of steam-tight combination valve lift and steam obstructions arranged 60 diametrically opposite each other and suitably fastened, together with a hollow shaft having a solid ring securely fastened onto it and whereon are suitably fastened said rotors in such a manner so that the pair of 65 combination valve lift and steam obstruc-

tions on each rotor are positioned diametrically perpendicular to each other, all substantially as shown, described and for the purpose set forth.

2. In combination with an annular steam 70 rotary motor having a suitable rotor housing, an annular steam rotary motor rotor having flanges extending from its annular surface in such a manner so as to form a channel that will expand sufficiently in the 75 rotor housing of the motor through the action of the steam pressure therein, so as to give the rotor the proper steam-tight fitting in the said rotor housing, substantially as shown, described and for the purpose set 80 forth.

3. In an annular steam rotary motor having a suitable casing and suitably housing rotors provided with flanges that form steam channels, and having combination 85 rocker-oscillatory valves with wings extending in opposite directions; a combination valve lift and steam obstruction which is suitably positioned and fastened in the said steam channels on the rotors of the motor, 90 and which consists of an obstruction or abutment having an elongated elevated surface with sloping ends, having steam obstruction chambers provided with perpendicular walls in which are positioned packing members, and having means to permit the steam pressure and expansion to act against the perpendicular walls of the said steam obstruction chambers, all substantially as described, shown and for the purpose set forth.

4. The combination in an annular steam 95 rotary motor having a suitable casing, of a motor rotor provided with flanges that form steam channels, of a combination valve lift and steam obstruction having an elongated elevated surface with sloping ends, having steam obstruction chambers provided with perpendicular walls in which are positioned 100 packing members, and having means to permit the steam pressure and expansion to act against the perpendicular walls of the said steam obstruction chambers; and of combination rocker-oscillatory valves having 105 wings extending in opposite directions, all 110 substantially as shown, described and for the purpose as set forth.

5. In an annular steam rotary motor having a suitable rotor housing and provided with combination rocker-oscillatory valves, 115 a combination rotor having flanges extending from its annular surface in such a manner so as to form channels, that are capable of expanding, together with two combination valve lift and steam obstructions, 120 each having sloping ends and elongated elevated surfaces and being suitably fastened into the said channels and positioned diametrically opposite each other so as to correctly operate and to give the proper move- 125 130

- ment to the combination rocker-oscillatory valves of the motor and which also are provided with cam shaped contrivances consisting of cam shaped bearings held in suitable seats by springs, thus in combination producing a steam tight fitting rotor in the rotor housing of the motor, all substantially as shown, described and for the purpose set forth.
10. In an annular steam rotary motor housing and annular steam rotary motor rotor provided with flanges which form channels, a reversible rocker exhaust valve consisting of a rocker having wings extending in opposite directions through which are longitudinal slots which allow the steam in the steam channels of the rotors of the motor, quick and easy escapement when the rotors are operated in either a forward or reverse motion, substantially as shown, described and for the purpose set forth.
11. In an annular steam rotary motor having rotors provided with flanges which form steam channels, a reversible rocker valve consisting of a rocker having wings extending in opposite directions whose ends contain a concave surface or cavity into which terminate steam outlet passages that pass through said wings of the valve in such a manner so that the resultant pressure in the steam channels of the rotors automatically balances the valve when it is in either a forward or reverse working position, substantially as shown, described and for the purpose set forth.
12. In combination with an annular steam rotary motor, a rocker valve consisting of a rocker having steam outlet ports so arranged in connection with concave surfaces in its ends, that the resultant pressure in the steam channels automatically balances the valve when in either a forward or reverse working position; having longitudinal slots in its wings to allow the exhaust steam quick and easy escapement, and having spring attachments for holding the rocker in either a forward or reverse working position, all substantially as shown, described and for the purpose set forth.
13. In an annular steam rotary motor, a valve bearing consisting of a tube having a flange whereby it is bolted onto the motor, having slots properly located for the passage of steam when required, having a shoulder or ridge to hold an oscillatory valve in place, having packing boxes, and being so machined that oscillatory valves can be snugly fitted in, and that rocker valves can be snugly fitted on it; thus acting both as a bearing and as a valve in combination with the oscillatory and rocker valves, substantially as described, shown and for the purpose set forth.
14. In an annular steam rotary motor oscillatory valve having slots, a steam lead tube which is placed inside the oscillatory valves and which consists of a tube carefully machined and suitably fastened at one end to a steam connection and closed at the other end so as to hold the steam pressure and thereby allowing the free movement of the valves without pressure friction, and having slots so located as to properly lead the steam to the valve slots, substantially as shown, described and for the purpose set forth.
15. In an annular steam rotary motor provided with rocker valves which are journaled onto stationary valve bearings having slots, a combination oscillatory valve consisting of a tubular valve snugly fitted into the valve bearing of the motor and having slots for the passage of steam, together with a steam lead tube which is snugly fitted into said tubular valve and designed to carry or hold the steam pressure so as to allow the oscillatory valve free and easy movement by being closed at the one end and held stationary by being fastened at the other end and which has slots so located as to lead the steam into the slots of the oscillatory valve, all substantially as shown, described and for the purpose set forth.
16. In an annular steam rotary motor, a combination reversible rocker-oscillatory valve consisting of a rocker having wings extending in opposite directions in whose ends are concave surfaces or cavities, through which pass steam outlet passages which terminate in said concave surfaces or cavities, through which pass longitudinal exhaust slots, and upon which are fastened spring attachments for holding the rocker in either a forward or reverse position; together with a valve bearing upon which the said rocker is journaled and which has a flange, a shoulder or ridge, and containing slots corresponding with the steam outlet passages in the said rocker; together with an oscillatory tubular valve which is snugly fitted into said valve bearing and having slots corresponding with the slots in the said valve bearing; and a stationary valve lead tube having slots so located as to lead the steam into the oscillatory valve slots by being snugly fitted in the said oscillatory valve and so designed as to hold the steam pressure by being closed at the one end, all substantially as shown, described and for the purpose set forth.
17. In an annular steam rotary motor having a hollow shaft with rotors suitably fastened thereon and having combination rocker-oscillatory valves, a steam cut-off device or timer consisting of a cylindrical ratchet which is operated by a controlling gear and placed inside the hollow shaft of the motor; together with said hollow shaft upon which is keyed a large camlike shaped disk having a set of gears suitably mounted

thereon which is in mesh with the said cylindrical ratchet, and also having a collar upon which is mounted a similar but movable large camlike shaped disk having a 5 crescent shaped ratchet suitably mounted thereon which is in mesh with the above mentioned set of gears and being held in place by a collar plate suitably fastened; together with valve levers which are in connection with the combination rocker-oscillatory valves of the motor and provided with suitable bearings, which bear on the camlike surfaces of the disks, thereby operating the valves to cut off the steam at regular intervals or at any desired time during the working stroke of the rotors by advancing the movable disk through the movement of the cylindrical ratchet in the hollow shaft of the motor, all substantially as shown, described and 20 scribed and for the purpose set forth.

14. In an annular steam rotary motor having combination rocker-oscillatory valves with wings extending in opposite directions, a reversing device consisting of a

controlling rod suitably placed and having 25 disks mounted thereon, together with suitably mounted circular levers upon which said disks act and which are in connection with valve spring lifts by means of gears and a shaft upon which are positioned said 30 valve spring lifts; together with valve springs suitably positioned on the wings of the combination rocker-oscillatory valves upon which act the valve spring lifts for either a forward or reverse movement of the 35 motor by causing either wing of the combination rocker-oscillatory valve to be in working position by a valve spring lift acting upon the spring attached to either wing, all substantially as shown, described and 40 for the purpose set forth.

In testimony whereof I have affixed my signature in presence of two witnesses.

LEONARD ADAMS.
